UNITED STATES PATENT OFFICE.

EDWIN LYMAN MAYALL, OF STOCKTON, CALIFORNIA, ASSIGNOR TO THE HOLT MANUFACTURING COMPANY, OF STOCKTON, CALIFORNIA, A CORPORATION OF CALIFORNIA.

VINEYARD-PLOW.

1,333,811.

Specification of Letters Patent. Patented Mar. 16, 1920.

Application filed August 25, 1915. Serial No. 47,251.

To all whom it may concern:

Be it known that I, EDWIN LYMAN MAYALL, a citizen of the United States, residing at Stockton, in the county of San Joaquin and State of California, have invented new and useful Improvements in Vineyard-Plows, of which the following is a specification.

This invention relates to plows, and pertains especially to a plow or cultivator adapted for work in vineyards, hop fields, and other places where the rows, or vines or trees are disposed at varying distances apart.

Heretofore in cultivating vineyards several serious problems have presented themselves in connection with any attempt at successful gang plowing, or plowing by power, or where more than one or two plows in a gang were employed.

Vineyards, and likewise hop fields, are usually planted with their vines arranged in rows, successive rows being disposed from 7 to 12 feet apart. In plowing between these vines it is essential that the soil in successive plowing be turned alternately toward the vines and from the vines, and that care be exercised to avoid contact with the vines, or their roots. Thus it is desirable in one season, or at one time during the season, to plow so that the soil is all thrown outwardly from the center toward two adjacent rows, and at a succeeding plowing that the soil be turned in the opposite direction. This generally calls for the employment of two different plows. The present invention provides a plow easily adaptable to turn the soil in whichever direction it is desired.

In vineyard cultivation, is the need of plowing deepest in the center between the rows and to have the furrows gradually grow shallower in depth toward the vines, so as not to injure the roots. The present invention arranges for an adjustment of the plows to plow at any desired depth, and also for an ingenious regulation of the suction of each plow.

Again, it is not infrequent for the vines in a row to be out of alinement, or for a vine to lean out of alinement, and it is therefore necessary in plowing to avoid injury to such vines as intrude into the space between the rows and at the same time it is equally important to plow up close to every vine. The present invention provides means whereby,

when the plow is close to the vines and the plows set to throw from the vines, the outer plows at each side of the gang are independently adjustable at the will of the operator, toward and from the line of draft, so that any vine or obstruction may easily be dodged.

By the design of my special two-throw plow (*i. e.*, a plow having its plows set so that there are two sets working simultaneously, either both throwing to the center or both from the center) a great saving of power is accomplished through equalizing side draft. In ordinary gang plows where all the plows turn the furrow in one direction, to right or left, there is a very heavy side draft in the direction of the land or away from the furrow. In my construction, this side draft is balanced and results in a consequent saving of approximately 40% in power required to pull a gang of given size.

There are other objects and advantages accomplished by this invention which will appear hereinafter.

The invention consists of the parts and the combination and construction of parts as hereinafter more fully described and claimed, having reference to the accompanying drawings, in which—

Fig. 16 is a plan view of same.

5 Figs. 17, 18, 19 and 20 show various arrangements of plows.

10 A—A represent two longitudinally extending plow beam frames constructed and arranged to carry the adjustable reversible plows B. These frames A—A are disposed one on either side of the center line of draft; these frames being made preferably of structural metal and of approximately rectangular shape, with the front ends of the 15 frames connected across by a chord 2 and a drop truss member 2'; the rear ends of the frames being inswept as shown at 3, to connect to the rear caster wheel casting 4, in a manner more particularly to be described 20 later.

20 Each of the plow beam frames A is preferably provided with an angular central member 5, suitably braced transversely at 6 and connected to the diagonal rear end portion 3; the forward end of the central partition member 5 spaced to accommodate the front non-swivel supporting wheels 7. The machine is supported at its front on two of said non-swiveling wheels 7, and at its rear 25 end on the swiveled caster wheel 8; the purpose of this method of support being indicated later. Each of the wheels 7 is journaled in an inverted-U-shaped standard 9, on which the frame is vertically slideable in 30 the guide castings 10; one of these castings 10 being bolted to the outside member of a beam frame A, and the complementary casting bolted to the forward reach of the partition member 5. The raising and lowering 35 of the frame on the standards 9 may be accomplished by any appropriate means. As here shown, each side of the frame is independently adjustable through the medium of the levers 11; each lever 11 being fast to a 40 respective rock shaft 12 journaled at the forward end of the beam frames A-A. Each rock shaft has a pair of cranks 13 straddling a wheel 7 and connected by links 14 to the lower ends of a standard 9. Rocking lever 45 11 correspondingly rocks a shaft 12 causing the frame to move up and down on its guide 50 9; each lever being held in place by an ordinary ratchet and quadrant mechanism 15.

In order to facilitate the lifting of the heavy frame when it is desired to raise the plows, a spring 16 is provided in connection with each lever, which has one end anchored to the frame and the other end adjustably connected to the lever, as shown at 17 on one side of the lever fulcrum.

In order to adjust the levers 11 to have them convenient to the operator, and to lie more or less flat with reference to the frame, each rock shaft 12 is provided with a cast 65 projection 18, which is perforated at dif-

ferent points to receive a locking bolt 19; the desired angle of the lever being obtained by inserting the bolt 19 through one or the other of the perforations in the projection 18. 20 is a draft connection for attachment 70 to suitable traction means, as a traction engine, indicated at 22.

The rear ends of the draft connections 20 are adjustably connected to the gusset plates 23, which are rigid with the plow beam 75 frames and extend therebeneath and are supported and attached to, and are braced by the drop truss 2'.

The rear diagonal inswept ends 3 of the beam frames A embrace between them a short beam member 25 which is secured at its forward end to the transverse brace 26; the rear ends of these parts 3 and 25 being bolted through and secured to a seat on the caster wheel casting 4, as shown in Fig. 10. 85 The caster wheel casting 4 is adapted to slide up and down on the standard 27 of caster wheel 8; there being front and rear anti-friction bearings 28-29 to reduce the power required to raise and lower the rear end of the frame on said standard 27. 90

The following means are provided for raising and lowering the rear end of the frame:

30 is an operating lever arranged in convenient reach of the operator's seat 31 and is loosely fulcrumed on a rock shaft 33, which in turn is journaled in and extends through the casting 4. Shaft 33 carries two spaced crank members 35-36 connected by respective links 37-38, and a cross head 39, which swivels on the upper end with the caster wheel standard 27. Lever 30 is adapted to be adjustably locked so as to cause the shaft 33 to turn in unison with lever 30 by means of a cast projection 41 on the hub 42 of the crank member 36; the bolt 43 fitting perforations 44 in the projection 41. This adjustable connection of lever 30 with its rock shaft is similar to the connections 18-19 of levers 11. Thus it will be seen that rocking lever shaft 33 is rocked to cause power to be transmitted through the cranks 35-36 to links 32-28 to raise and lower the rear end of the frame; the caster wheel 8 at all times trailing idly at the rear. Lever 30 is held at any desired point by the usual ratchet and quadrant.

The plows B are arranged in two gangs, one gang for each beam frame A, and the two gangs so set that in throwing their furrows they will 'balance' one another. That is, plows in each gang are so set that both gangs will turn their furrows all toward the center, or all away from the center. Furthermore, these plows are adapted to be interchangeable, not only one with the other in the same gang, but one gang with the other, so that the same set of plows at one time will throw all their furrows outwardly

toward the vines, or they will throw their furrows inwardly away from the vines. In addition to this, each plow is vertically adjustable independent of the other, so that 5 furrows of different depths in the same gang, or both gangs can be plowed.

These various adjustments and functions of interchangeability are effected in the following manner, which practice has shown 10 to be thoroughly practicable:

Each plow has a vertical shank 45, preferably of structural metal, adjustable in specially designed guide brackets 46 and locked to some suitable portion of the beam 15 frames A by appropriate means as the clamps 47. The brackets 46 are pivotally connected at one end, as at 48, to frame A; the other end of the brackets 46 having a vertical slot 49 to receive a bolt 50 and allow 20 for the tilting adjustment forward and back of bracket 46 to correspondingly raise or depress the toe or point of a plow, and so decrease or increase the plow suction. By 25 plow suction is meant the tendency of the plow to run more or less into the ground.

In order to set the plows for proper suction and prevent movement of the brackets 46 after tightening the bolt 50, there are provided set screws 51 threaded in a lug 52 30 on the bracket 46, so that the screws 51 may bear against the underside of the frame A and resist any tendency of a bracket 46 to rock on its pivot 48.

A further advantage is that this set screw 35 provides a gage for the proper setting of the bracket 46 when the plows are transposed from one position on frame A to another position. Thus, when bracket 46 is transposed by placing the bracket with said screw 40 against bottom of frame A, it will provide for the proper setting of plow bottom. Thus transposing plow bottoms in this way need not change the suction or proper setting of the plow bottoms.

45 When plowing to throw the furrows toward the vines, or away from the center line of draft, the plows are set one behind the other in echelon, as shown in Fig. 1, the rear plows B being spaced only a couple of 50 inches apart. In this case a colter wheel 55 is employed having a fixed standard 56, and operating between the two rearmost plows, so that practically all the land is broken or pulverized by the conjoint action of the 55 plows and colter. Where the rows are wider apart than the ordinary outward throw of the plows, I may increase the extreme outward throw of the plows by means of outriggers 60, Fig. 2, secured forward and to 60 the outside of frames A; the brackets 46 for these two forward outermost plows being secured to the outriggers 60 in the same manner that the brackets are secured to the main portions of the frames A. These outriggers 65 increase the width of the furrow

cuts by approximately twenty inches; the other plows being set one behind the other at suitable points on their frames A.

When the machine is to be set to throw the furrows inwardly toward the line of draft and away from the vines, the colter wheel 55 may be dispensed with. With the plows set to throw inwardly away from the vines they must as a rule, come much closer 75 to the vines than where the furrow is thrown toward the vines. Consequently in order to give greater over-all spread to the plows and to enable the operator to dodge any vines which are out of line, or project into the area between the rows, there are provided the supplemental adjustable lateral plow beams 61; there being one beam on each side of the machine pivoted near the forward end thereof, and each beam independently adjustable toward and from the 80 line of draft. Preferably these beams are made of two strong bars of metal connected at their forward ends to a block 62; block 62 being loose on a fulcrum pin 63, which passes upwardly through an adjustable 85 bracket 64. The upper surface of block 62 has a conical bearing 65 fitting a similar seat in the under-side of bracket 64. A brace member 66 springs from the beam 61 and connects to a bearing block 67 having 90 a similar underneath conical bearing 68, fitting in a similar socket in the bracket 64. The purpose of the conical bearings 65-68 is to take up wear and avoid vibrations otherwise resulting from the severe strains 95 placed upon the swinging beam 61.

It is manifest that the fulcrum for the plow beam 61 being so far from the plow the tendency to vibration is quite great and it is necessary to provide a rigid and stable 105 construction which will at all times insure a good and perfect fit at the joints.

The bracket 64 is fulcrumed to its beam A at 70 on one side of pin 63, while the other end of the bracket on the opposite 110 side of pin 63 is made vertically adjustable so as to regulate the suction of the plows, carried by the swinging beam 61. This suction regulation is accomplished by means of a block 71 mounted by a wooden or easily 115 friable pin 72 on frame A, and working in a vertical slot 73 on the bracket 64; the block 71 being vertically adjustable and secured by set screws 74. The outer end of the wooden pin 72 is supported in a steel 120 clip 75. The purpose of this wooden pin 72 is to permit the plow B mounted on beam 61 to trip through the shearing of this pin 72, if at any time this bottom should snag a root of the vines. In other words, the pin 125 72 will break off before the root breaks, so as to save the latter from injury. The block 71 containing pin 72 is so secured that when the pin is sheared or the plow bottom trips the set of the plow bottom is in no 130

way affected, or disarranged due to the fact of tripping and by restoring a new pin through block 71 restores the correct setting of plow bottom B.

- 5 The lateral adjustment of plow bottom B attached to each swinging beam 61 toward and from the vines is accomplished by means of respective levers 76. These levers are located in front of and convenient to the operator's seat 31. Each lever is fulcrumed at 77 and connects with a respective bell crank 78 by means of a link 79; the opposite ends of the bell cranks being connected with their respective swinging beam 61 by means 10 of a link 80. The position of the levers is maintained by the usual ratchet and quadrant.

Thus it is seen that each plow beam 61 with its plow is independently operable 20 from the operator's seat toward and from the vines without varying the direction of travel of the machine; each plow beam being controlled by its respective lever 76.

Among the various practical features of 25 importance in connection with this machine is the fact of having its front end mounted on two non-swivel wheels, and its rear end on a swiveling or caster wheel in conjunction with the comparatively short coupling 30 20 to the traction engine, which enable the machine to follow close in the wake and path of the tractor, and thus make the necessary short turns required usually at the end of a row, and between the row terminals and the field boundary, known as the "head lands". This short turn feature is quite important in the matter of a gang plow.

With this plow is combined all the essentials of a practical, reversible gang plow capable of throwing all its furrows outwardly, or all its furrows inwardly; it is possessed of a great degree of flexibility in width of plow area accomplished in a single 40 traverse of the machine. This reversibility and transverse flexibility is accomplished by changing from one side of the machine to the other the brackets 46 and their plows, and either employing the outriggers 60, or the swinging beams 61, depending on conditions. The vertical adjustment of the plows to plow deeper or shallower from one side toward the other is accomplished by adjusting the plow shanks 45 and their clamps. 45 The suction of the plows is changed by tilting the plow shank brackets 46 more or less; or in the case of the outside swinging plows, adjusting the position of the block 71. The vertical adjustment of the plows may also 50 be controlled by the levers 11-30. The line of the outer furrow when throwing the furrow away from the vine, and the swinging beams 61 are employed, is bent without

changing the travel of the machine, through the medium of one or the other of the levers 65 76. The tripping of either of these outside plows on beams 61 is permitted by the use of the friable wooden pin 72.

It is obvious that various changes in details of construction may be made in this 70 machine without altering its principle, or departing from the spirit of the invention.

It is manifest that all of these operations of control of the machine and the plow, with the exception of changing the suction of the 75 plow bottoms, are effected from the operator's seat.

Having thus described my invention what I claim and desire to secure by Letters Patent is:—

1. In a mold board gang plow, the combination of a rigid frame, supporting wheels on which the main frame is adjustable vertically, a series of plows having right-hand mold boards mounted at one side of the 85 center of the frame and a series of plows having left-hand mold plows mounted at the other side of the center of the frame, the plows of one series being removable and interchangeable with the plows of the other 90 series, said rigid frame comprising a pair of spaced longitudinally extending beams at each side of the center thereof connected together to form a substantially rectangular shaped frame member, transverse members 95 connecting the two pairs of beams together, each of said beams being arranged to receive a plow, a member at the center line between said pairs of beams arranged to carry a plow on either side and a member between the 100 individual beams of each pair arranged also to receive a plow.

2. In a mold board gang plow, the combination of a rigid frame, supporting wheels on which the main frame is adjustable vertically, a series of plows having right-hand mold boards mounted at one side of the center of the frame and a series of plows having left-hand mold plows mounted at the other side of the center of the frame, the 105 plows of one series being removable and interchangeable with the plows of the other series, said supporting wheels comprising a pair of non-swivel wheels at the front end of the frame and a single swivel wheel at 110 the rear end of the frame near the outer limits thereof and a vertically adjustable bracket for each of said wheels connected to the frame.

In testimony whereof I have hereunto set 120 my hand in the presence of two subscribing witnesses.

EDWIN LYMAN MAYALL.
